INVENTOR

James Mac Gregor
By John C. Watson

ATTORNEY

UNITED STATES PATENT OFFICE.

JAMES MACGREGOR, OF BRAINTREE, MASSACHUSETTS.

DEVICE FOR DISTRIBUTING SAND.

1,363,185.

Specification of Letters Patent. Patented Dec. 21, 1920.

Application filed October 24, 1918, Serial No. 259,542. Renewed November 9, 1920. Serial No. 422,970.

To all whom it may concern:

Be it known, that I, JAMES MACGREGOR, a citizen of the United States of America, residing at the town of Braintree, in the 5 county of Norfolk and State of Massachusetts, have invented certain new and useful Improvements in Devices for Distributing Sand, of which the following is a specification.

10 My invention relates to a device for uniformly spreading or distributing a layer of stone, screenings, sand, cement, lime, phosphate or any similar material where such is required and the object of my invention is to provide a rapid and efficient 15 means for distributing a uniform layer of sand over the surface of a freshly oiled or tarred highway; together with such other elements and combinations as are herein- 20 after more particularly set forth.

I accomplish these objects by means of the mechanism illustrated in the accompanying drawings, in which:

Figure 1 is a plan view of my device.

25 Fig. 2 is a side view or elevation with the near side of the body removed to show the interior.

Fig. 3 is a rear view with the seat and crank shaft not shown.

30 Fig. 4 is a bottom view.

Fig. 5 is a detail view showing the method of moving the screen.

Fig. 6 is a detail view of the gears used 35 to regulate the rate of distribution of the material.

Similar numbers refer to similar parts throughout the several views.

The ordinary method of applying the "blotting coat" on a highway, with shovels, 40 is slow and it is impossible to secure a uniform distribution. My device will be particularly useful in cities where it is customary to apply a thin layer of sharp sand on smooth pavements which, because of ice 45 or sleet thereon, make traffic precarious, and the farmer or gardener may use it in spreading plaster or phosphate over his land.

1, represents the floor of a truck or wagon 50 upon which my device may be constructed. 2, is the bottom of the hopper into which the material is placed, one end of which may be elevated by the screws 3, to give the proper slope. The bottom, 2, is hinged at 55 the lower end by hinge, 22. 4 and 5, are

the sides of the body of the wagon which may form the sides of the hopper.

At the lower end of the adjustable bottom, 2, the floor, 1, is cut away forming a rectangular opening extending across the 60 bottom of the hopper. Beneath the opening is the screen or sifter, 6, which slides horizontally in the guides, 7, 7. Attached to the forward end of the screen, 6, is the connecting rod 8, operated by the crank shaft, 65 9, which is in turn revolved by the chains, 10, 10, driving the sprocket wheels, 11, 11, by means of the sprocket wheels, 12, 12, which derive their power from the rear 70 wheels, 13, 13, of the truck or wagon to which they are attached.

It will appear from this arrangement that the rear wheels of the truck or wagon, revolving as the vehicle is drawn or propelled, will transmit a reciprocating motion to the 75 screen, 6, between the guides, 7, 7, and the material falling from the hopper on to the screen will be sifted through and fall upon the ground.

In order to regulate the rate at which 80 the material flows from the hopper to the screen, 6, I provide the following means for controlling the width of the opening in the bottom of the hopper. 14, is a hand wheel for the operator, who sits in the seat, 85 15. Attached to the shaft of the hand wheel is a gear, 16, which meshes with the gears, 17, 17, on either side. The gears, 17, 17, are attached to and operate screws, 18, 18, which thread into a fixture, 19, attached to 90 slide, 20.

It is apparent that by turning the hand wheel, 14, the slide, 20, will be raised or lowered by the screws 18, 18, and thus regulate the opening in the bottom of the hopper. 95

In order to protect the controlling gears and screws, I provide a hood or cover, 21, which is placed over them.

It is to be observed that any size mesh 100 can be placed in the screen, 6, so that the device may be readily adapted to distribute coarse or fine material.

What I claim as my invention and desire to secure by Letters Patent is:

105 1. In a device of the character described, a running gear; a body having a hopper-shaped bottom mounted upon said running gear; a discharge opening in said hopper bottom; means for varying the size of said 110

- discharge opening; means for varying the incline of a major portion of said hopper bottom; a perforated screen slidably mounted beneath said opening; a crank shaft rotatively mounted on the under-side of said body; a connecting rod joining said screen to said crank shaft, whereby the rotation of said crank shaft will impart a reciprocating motion to said screen; and means 5 for operating said crank shaft from the wheels of the running gear.
2. In a device of the character described, a body having a hopper bottom mounted on said running gear; a discharge opening in said hopper bottom, one portion of said hopper being hinged near said opening and provided with means for changing the angle of incline of said hinged portion; a slide adapted to vary the size of said opening; means for operating both ends of said 10 slide simultaneously from a single hand wheel; a perforated screen slidably mounted beneath said opening; bearings attached to the underside of said body; a crank shaft rotatively mounted in said bearings; a connecting rod joining said screen and said crank shaft, whereby the rotation of said crank shaft will impart a reciprocating motion to said screen; sprocket wheels mounted on the ends of said crank shaft; sprocket 25 wheels mounted on an axle of the running gear and adapted to be driven by the wheels of said running gear; and sprocket chains connecting the sprocket wheels on the crank shaft with the sprocket wheels on the axle, 30 substantially as described.
- 15 In testimony whereof I have affixed my signature.

JAMES MacGREGOR.
